(57) **CLAIM**

The ornamental design for a box as shown and described.

DESCRIPTION

FIG. 1 is a front, bottom perspective view of the box;

FIG. 2 is a rear, left perspective view thereof;

FIG. 3 is a bottom, right perspective view thereof;

FIG. 4 is a front view thereof;

FIG. 5 is a rear view thereof;

FIG. 6 is a right view thereof;

FIG. 7 is a left view thereof;

FIG. 8 is a top view thereof;

FIG. 9 is a bottom view thereof; and,

FIG. 10 is a partially enlarged view of FIG. 2.

The broken lines shown in the drawings depict portions of the box that form no part of the claimed design. The long dash-short dash in FIGS. 2 and 9 show the boundary of the enlarged view and form no part of the claimed design.

1 Claim, 10 Drawing Sheets
